WHEEL

Thomas L. Hibbard, Birmingham, Mich., assignor to Kelsey-Hayes Company, Romulus, Mich., a corporation of Delaware

Filed Jan. 26, 1966, Ser. No. 771

Term of patent 14 years

(Cl. D14—30)

FIGURE 1 is a plan view of a wheel showing my design;

FIGURE 2 is a sectional view thereof taken along the line 2—2 of FIGURE 1;

FIGURE 3 is an enlarged sectional view thereof taken along the line 3—3 of FIGURE 1;

FIGURE 4 is a perspective view thereof; and

FIGURE 5 is a perspective view of a wheel showing a somewhat modified form of my design.

The characteristic features of my design reside in the portions shown by means of full lines in the drawing. The outwardly visible surfaces of the wheel body which are stippled in the drawing are of a dark coloration contrasting with the outwardly visible surfaces of the wheel body which are not stippled in the drawing.

I claim:

The ornamental design for a wheel, substantially as shown and described.
